UNITED STATES PATENT OFFICE.

CHARLES A. REDINGER, OF WALNUT, INDIANA.

RAIL-TIE.

SPECIFICATION forming part of Letters Patent No. 761,323, dated May 31, 1904.

Application filed February 18, 1904. Serial No. 194,159. (No model.)

To all whom it may concern:

Be it known that I, CHARLES A. REDINGER, a citizen of the United States, residing at Walnut, in the county of Marshall and State of Indiana, have invented certain new and useful Improvements in Rail-Ties, of which the following is a specification.

The object of my invention is to produce a metallic railway-tie of such character that while possessing all of the advantages of that type of tie will nevertheless afford for the rails the same elastic support offered by wooden ties, the arrangement being such that the pillow-blocks may be readily removed and replaced without disturbing the main body of the tie, and therefore without unsettling the ballast of the road-bed or involving the re-laying of the ties.

The accompanying drawings illustrate my invention.

Figure 1 is a perspective view of a tie with attached rails. Fig. 2 is a similar view of a modification. Fig. 3 is a similar view of another modification, and Fig. 4 a detail sectional view.

In Fig. 1 of the drawings, 10 indicates the main metallic channel-body of the tie. Secured to the main body 10 at each end is a pair of metallic loops 11 11, the upper member 12 of each extending across the channel and lying substantially parallel with the web. The member 12 is cut away along its inner edge to form a space 13, and thus leaving at each end a projection 14, adapted to engage the base of the rail. The loops may be braced against lateral displacement by broadening the bases, as shown in the drawings, or by means of braces suitably attached. They are shown as secured by rivets 20. The dimensions of the space between the main body and the loops is such that a pillow-block 15 may be inserted therein. The rail 16 is then placed on this pillow-block and secured thereto by suitable means, as spikes 17, which pass through the spaces 13. Lateral displacement or spreading of the rails is prevented, because the base of the rail lies between and is engaged by the adjacent edges or portions 14 of the loops.

In Fig. 2 the parts are similar except that 50 the main body is a simple sheet or strip of metal 10'.

In Fig. 3 I have shown a form which can be made from old rails. Here the main body 10" is made of the base and web of worn rails, 55 the head being removed and rolled into short channel-pieces 18, suitably attached to the top of the T of the main body. The loops 11 and the remaining portions are as in Fig. 1. The main body 10" may be formed of the 60 whole rail, if desired, and the channels 18 attached, as will be readily understood.

It will be noticed that the rails are supported on the elastic pillow-blocks, yet they are positively tied together by the metallic 65 main body. In case a pillow-block becomes worn the spikes may be withdrawn and the pillow-block removed and a new one substituted without disturbing the setting of the main body of the tie in the road-bed. The 70 pairs of loops 11 may be integral, with a sufficient amount removed from the upper member to receive the rail and the spikes.

I claim as my invention—

1. The combination, with a metallic tie, of 75 a pair of loops secured to said tie at each end and extending thereover, said loops being arranged to form a receptacle for a pillow-block and to receive a rail therebetween.

2. The combination, in a metallic tie, of a 80 channeled body, and a pair of loops secured thereto and extending thereover to receive a pillow-block, said loops being arranged to receive a rail therebetween.

3. The combination, in a metallic tie, of a 85 main body channeled to form pillow-block seats, pillow-blocks secured thereto one at each end, and a pair of loops extending over the channeled seat and the pillow-block and arranged to receive and retain the rail. 90

4. The combination, in a metallic tie, of a main tie member, a pair of pillow-block pockets secured thereto formed to hold the rails against lateral displacement, and having openings through which the spikes may pass, pillow-blocks secured within said pockets and upon the main body, the rails, and spikes entering said pillow-blocks and holding the rails there-

to and said rails being also supported by the adjacent edges of the pocket structures.

5. The combination, in a metallic tie, of a main tie member, a pair of pillow-block and rail holders at each end of the main tie member arranged the width of a rail-foot apart whereby when a rail is placed therebetween it is held from lateral displacement and wherein pillow-blocks may also be secured, said pil-

low-blocks, and means for securing the rails to said pillow-blocks when in position.

In witness whereof I have hereunto set my hand and seal, at Indianapolis, Indiana, this 11th day of February, A. D. 1904.

CHARLES A. REDINGER. [L. S.]
